UNITED STATES PATENT OFFICE.

ERA C. JACOBSON, OF OAK PARK, ILLINOIS, ASSIGNOR, BY MESNE ASSIGNMENTS, TO AMERICAN STEAM TRUCK COMPANY, OF CHICAGO, ILLINOIS, A CORPORATION OF DELAWARE.

BOILER.

Application filed April 24, 1919. Serial No. 292,361.

To all whom it may concern:

Be it known that I, ERA C. JACOBSON, a citizen of the United States, residing at Oak Park, in the county of Cook and State of Illinois, have invented a certain new and useful Improvement in Boilers, of which the following is a specification.

My invention relates to an improved boiler construction of the sectional type in which the tubes contain the water and the fire from the furnace surrounds the tubes. My invention is characterized by the use of a plurality of sections which are similar, in alternate arrangement so as to afford ready facilities for mounting the sections in place and for removing any section or sections if it may be necessary in order to repair the boiler. By this arrangement also, the space above the furnace is completely utilized to heat the water in the water tubes, and as a result efficient operation of the boiler as a whole is secured. The units are preferably constructed by securing a plurality of similar water tubes between end headers, preferably by means of fusing the tubes to the headers, as for example by means of the oxy-acetylene flame so that the units, when completed, are practically homogeneous sections. In constructing the unit, I prefer to make the water tubes slightly curved so that there will be no undue strain locally upon the header as a result of unequal expansion and contraction of the several water tubes of any one unit.

By my construction, the headers at one end of the unit are disposed in lower position than the headers at the other end of the unit, and the upper headers are connected in any suitable manner to a steam drum which is connected by suitable pipes with the lower headers so as to maintain them full of water at all times, the water level in the steam drum being preferably maintained slightly above the connection to the lower headers. By my construction, shields are provided in the steam drum to prevent the steam entering the drum from the upper header, being projected directly to the outlet opening from the drum and thus carrying with it water which may be entrained in the

steam. In my construction I also provide preheating coils for heating the water before it is delivered to the heating units of the boiler and also superheating coils for superheating the steam after it is delivered from the steam drum and before it is delivered from the boiler to the engine to be driven.

My invention will best be understood by reference to the accompanying drawings showing preferred embodiments thereof in which—

Fig. 1 shows the preferred form of my boiler in front elevation, the casing being removed to more clearly show the boiler parts,

Fig. 2 shows the parts seen in Fig. 1 in side elevation,

Fig. 3 shows in a view similar to Fig. 1 a modified construction of boiler sections as arranged and placed in a boiler, and

Fig. 4 shows in a view similar to Fig. 2 the construction in side view shown in Fig. 3.

Similar numerals refer to similar parts throughout the several views.

As shown in Figs. 1 and 2, the boiler consists of a plurality of sections 10 and 11, disposed in alternate arrangement throughout the boiler. Each section 10 consists of water headers 12 and 13 between which the water tubes 14 are located. These tubes 14 are slightly curved and are connected at their ends, preferably by fusion, to the headers 12 and 13, as a result of which the joints between the tubes and the headers are practically homogeneous with the structure of the tubes and headers itself, and, therefore, the heating and cooling of the parts cannot produce unequal strain at the joints, and furthermore, the curved construction of the water tubes results in permitting any tube which may be subjected to unusual expansion to spring away from its original path slightly so as to relieve the joint at the headers from undue strain. Each of the sections 11 consists of headers 15 and 16 between which the water tubes 17 are secured in the manner above described for the tubes 14. The units 10 and 11 are of the same general construction, differing only in details of construction permitting their assembly in the furnace to

completely utilize the space of the furnace and to better facilitate removing any particular unit if desired. Projecting flattened lugs, as shown at 18 and 19 are provided for 5 closing the upper ends of the headers 12 and 15 and for engaging the rods 20 and 21 respectively. Each of the upper headers 13 and 15 is similarly closed at its lower end and provided with a flattened lug, as shown 10 on 22 and 23 for engaging the rods 21 and 20 respectively. The lower ends of the headers 12 and 16 are connected by union connectors 24 and 25 with water supply pipes 26 and 27, which are of large enough size to 15 also constitute mud drums for the boiler. The pipes 26 and 27 are connected at the rear end of the boiler by a pipe 28 which in turn is connected with a water supply pipe 29, which pipe receives its supply of water from the 20 preheating coils 30 located in the top of the boiler and which are supplied from the water supply pipe 31. The pipes 26 and 27 are also connected at their rear end by pipes 32 and 33 with the lower portion of a steam 25 drum 34 so that the water which collects in the steam drum readily finds its way back to the water pipes 26 and 27 and thence to the lower headers 12 and 16.

The upper ends of the upper headers 13 30 and 15 are connected by pipes 35 and 36 through union connectors 37 and 38 with the sides of the steam drum 34, in which deflectors or shields 39 and 40 are disposed adjacent the openings into the drum 34 to 35 direct the steam and any water that may be entrained therein downwardly in the drum 34 away from the outlet pipe 41 connected with the upper part of the drum to carry steam from the drum to the super- 40 heating coils 42 and 43 from which the steam is delivered from the boiler to the pipe 44.

It is to be noted that as a result of the arrangement of the water pipes 14 and 17 45 that the superheating pipes 43 may be located below the water heating units just sufficiently above the fire from the furnace as to not over heat the superheating coils 43.

As shown in Fig. 1, the heat for the boiler 50 is generated by means of a liquid fuel burner 47, arranged to project its flame horizontally against a baffle of fire brick, or similar material, 48, which by being heated to white 55 heat radiates the heat to the boiler tubes over it. The water pipes 26 and 27 are provided with blow off cocks 45 and 46 for cleaning the mud from the said water pipes as desired.

It is to be noted that although the water 60 headers of the several water heating sections are of considerably larger diameter than the water tubes between the headers, that the water tubes may be located practically in contact with each other since the headers

at the end of the water heating sections are 65 alternated; that is to say, the right and left hand headers of the section 10 near the observer in Fig. 1 are the lower and upper headers respectively of said section, the next section is section 11 having its right and 70 left hand headers 15 and 16 above and below the headers 12 and 13 respectively, the next section is another section 10 and then another section 11, and so on across the 75 boiler, as a result of which the entire space from front to rear of the boiler is available 80 for the headers 12 which are the headers of alternate sections of the boiler while the same is true of the headers 15 which are the headers of the intermediate sections of the 85 boiler and that each header may occupy twice the space from front to rear that is required for the water tubes themselves. The water tubes of the several sections may be thus brought closely together leaving ample room for the larger headers and as a result of the alternate inclination of the water tubes of the several sections, the heat from 90 the furnace finds its way up to the water tubes and necessarily comes in contact with practically the entire outer surface of the 95 said water tubes in passing upward through the boiler. The water level of the boiler is preferably just above the connection of the pipes 32 and 33 to the steam drum 34.

When it is desired to remove a particular section from the boiler, the rods 20 and 21 are removed, the corresponding union connectors are undone and the particular unit which is to be removed may be taken from 100 the boiler without disturbing the remaining parts.

As a result of the construction described, it will appear that each unit or section of the boiler is similarly located with respect 105 to the furnace and thus operates equally efficiently, that each unit is located so that it has good water circulation through it at all times for effectively heating the water contained in it and that steam is delivered 110 from each heating unit to the steam drum in relatively dry condition and that the steam delivered from the steam drum to the pipe 41 is practically free from entrained water.

In the construction shown in Figs. 3 and 4, the boiler sections 49 and 50 consist of lower vertical headers 51 and 52 and upper horizontal headers 53 and 54 between which curved water tubes 55 and 56 extend. The headers 51 and 52 are connected in substantially the manner above described with water supply pipes 57 and 58, the rear ends of which are connected together by a pipe 59, which in turn is connected with a supply pipe 60 connecting the pipe 59 with the preheating coils 61, which coils are supplied with water by a pipe 62. The water supply pipes 57 and 58 are connected by pipes 63

and 64 with the lower portion of the steam drum 65, which has connected with its upper portion an outlet pipe 66 leading to superheating coil 67 from which the steam is discharged from the boiler through pipe 68. The upper headers 53 and 54 are connected in substantially the manner above described with the sides of the steam drum 65, the principal difference being that these headers 10 are above the water line instead of being below it as described above for the construction shown in Figs. 1 and 2.

The mode of operation of the construction shown in Figs. 3 and 4 is substantially 15 the same as that shown in Figs. 1 and 2, the principal difference being in the mechanical construction of the unit sections of the boiler, for in the case shown in Figs. 3 and 4, the several water tubes are of different lengths 20 for any given section instead of being the same length as shown in Fig. 1, thus necessitating somewhat greater expense in manufacture of the type shown in Fig. 3. In the construction of Fig. 3, there is the advantage 25 that the supporting rods shown in Fig. 1 are not required, thus making the removal of any desired unit easier than is the case in Fig. 1. The water heating units in Fig. 3 are in alternate arrangement substantially 30 as described above in connection with Fig. 1 with the same advantages there stated.

While I have shown my invention in the particular embodiments above described, I 35 do not, however, limit myself to these exact constructions in carrying out my invention as I may employ equivalents thereof known to the art at the time of the filing of this application without departing from the 40 scope of the appended claims.

What I claim is:

1. In a boiler, the combination of a plurality of units arranged in alternate relation in vertical planes, each unit consisting of 45 two substantially parallel headers and tubes of substantially the same length connecting said headers, said tubes being curved in the same direction and to substantially the same degree throughout their length, the tubes 50 of alternate units extending upwards towards one side of the boiler and the tubes of intermediate units extending upwardly towards the other side of the boiler and in close proximity to the tubes of the alternate units, whereby the upper headers on either 55 side of the boiler are entirely above and inclined to the lower headers on the same side of the boiler, connections for supplying water to and delivering steam from said 60 units, the adjacent ends of the headers on either side of the boiler being flattened and overlapping each other, and a rod on each side of the boiler extending through all of said flattened ends on that side of the boiler.

2. In a boiler, the combination of a plurality of units arranged in alternate relation in vertical planes, each unit consisting of two substantially parallel headers and tubes of substantially the same length connecting said headers, said tubes being curved in arcs 65 of circles throughout their length with their concave sides downwards, the tubes of alternate units extending upwards towards one side of the boiler and the tubes of intermediate units extending upwardly towards the other side of the boiler and in close proximity to the tubes of the alternate units, whereby the upper headers on either side of the boiler are entirely above and inclined to the lower headers on the same side of the boiler, connections for supplying water to and delivering steam from said units, the adjacent ends of the headers on either side of the boiler being flattened and overlapping each other, and a rod on each side of the boiler extending through all of said flattened ends on that side of the boiler.

3. In a boiler, the combination of a plurality of adjacent units disposed in vertical planes, each unit consisting of end headers and tubes between said headers, the tubes of alternate units being inclined upwardly in one direction and the tubes of intermediate units being in close proximity to the tubes of the alternate units and extending upwardly in the opposite direction to bring the headers of alternate units above the headers of intermediate units on the same side of the boiler with the adjacent ends of said headers overlapping each other, and a rod extending through all of said overlapping ends on each side of the boiler.

4. In a boiler, the combination of a plurality of adjacent units disposed in vertical planes, each unit consisting of end headers and tubes between said headers, the tubes of alternate units being inclined upwardly in one direction and the tubes of intermediate units being in close proximity to the tubes of the alternate units and extending upwardly in the opposite direction to bring the headers of alternate units above the headers of intermediate units on the same side of the boiler with the adjacent ends of said headers overlapping each other, a rod extending through all of said overlapping ends on each side of the boiler, and spacing members on each rod between the overlapping ends thereon.

5. In a boiler, the combination of a plurality of adjacent units disposed in vertical planes, each unit consisting of end headers and tubes between said headers, the tubes of alternate units being inclined upwardly in one direction and the tubes of intermediate units being in close proximity to the tubes of the alternate units and extending upwardly in the opposite direction to bring the head-

ers of alternate units above the headers of intermediate units on the same side of the boiler with the adjacent ends of said headers overlapping each other, a rod extending 5 through all of said overlapping ends on each side of the boiler, and spacing members on each rod between the overlapping ends there-

on, the ends of each rod being threaded and engaging nuts to clamp the overlapping ends thereon.

10

In witness whereof, I hereunto subscribe my name this 31st day of March, A. D. 1919.

ERA C. JACOBSON.
